DIE CASTING MACHINE

George L. Cherry, Western Springs, Ill., assignor
to Western Electric Company, Incorporated, a
corporation of New York

Application January 11, 1934, Serial No. 706,194

2 Claims. (Cl. 22—93)

This invention relates to die casting machines, and more particularly to a core actuating mechanism for a die casting machine.

An object of this invention is to provide a simple and efficient core actuating mechanism for a die casting machine, or the like, the mechanism being readily adapted to accommodate variously arranged cores for different dies.

In accordance with the general features of this invention as applied to a mechanism for actuating the cores of a die casting machine of a usual type employing a die comprising cooperating, movable and stationary die parts, there are provided in one embodiment three core actuating motive fluid cylinders adapted to be permanently mounted radially around the die on a mounting plate for the stationary die member. The piston of each cylinder is connected to actuate a slide guided in the mounting plate for the stationary die member for movement toward and away from the die so that cores may be withdrawn from three sides of the die, each slide adapted to carry at its inner end an interchangeably mounted adaptor plate by means of which variously arranged cores may be used with dies for various articles.

Other objects and advantages of this invention will more fully appear from the following detailed description, taken in connection with the accompanying drawings, wherein

Fig. 1 is a fragmentary side view, partly in section, of a die casting machine embodying the core actuating mechanism of this invention, the die parts being shown in their closed position;

Fig. 2 is a vertical section taken on the line 2—2 of Fig. 1, and

Fig. 3 is an enlarged vertical section taken on the line 3—3 of Fig. 2.

Referring now to the drawings, and particularly to Fig. 1, wherein the improved core actuating mechanism is illustrated in connection with a die casting machine of a usual type, shown fragmentarily, which comprises movable and stationary die parts 10 and 11, which are carried upon movable and stationary vertical plates 12 and 13, respectively, the movable die plate 12 may be reciprocated by actuating mechanism (not shown) connected thereto by a link 14 to move the die member 10 into and out of engagement with the die member 11 during the casting operation, the die plate 12 being suitably supported during its reciprocation upon the machine frame, indicated at 15.

The die parts 10 and 11, in the embodiment shown, when in abutting relation, as shown in

Fig. 1, provide a casting cavity 18 which is shaped to mold a casting 19 having three sets of apertures spaced 90° apart, each set comprising three apertures indicated at 20, 21, and 22, the apertures 21 being deeper than the other sets of apertures with some of the apertures aligned with each other and with the parting line, indicated at 25, of the die parts 10 and 11. The apertures 20, 21, and 22 are formed by appropriate cores 26, 27 and 28, respectively, which are inserted in and retracted from the casting cavity 18 in timed relation with the closing and opening of the die parts 10 and 11. Formed in the opposed inner engaging surfaces of the die parts 10 and 11 are complementary sets of depressions 29 for slidably receiving certain of the cores 26, 27 and 28, while the other cores are received in apertures 30 formed in the stationary die part 11, the cores being withdrawn from the casting 19 when the cast metal starts to cool and shrink.

An individual hydraulically actuated mechanism is associated with each set of cores 26, 27, and 28 for advancing them into operative position relative to the casting cavity 18 and withdrawing them from the cast metal forming the casting 19, two of the hydraulic mechanisms being indicated in general at 33 and 34 spaced 90° apart, the hydraulic mechanism which is connected to the cores 26 being omitted to conserve space. Since the hydraulic mechanism associated with each set of cores 26, 27 and 28, respectively, are identical, unless otherwise described, only one such mechanism, namely, mechanism 34, will be described.

Integral with the stationary die plate 13, one for each of the three hydraulic mechanisms, and radiating from the die 11, are three arms 35, two of which show in the drawings (Fig. 2), formed with parallel inclined slideways 36, upon which is mounted a one piece hollow slide 38 provided with a rectangular shaped opening 39. One of the slideways 36 is removably secured to the arm 35, as indicated at 40 (Figs. 1 and 2), to permit the slide 38 to be readily mounted upon and removed from the arm. Secured to the left side of the arm 35 (Fig. 1) and projecting freely into the opening 39 of the slide 38 is a motive fluid cylinder 41. The particular cylinder 41 to be described is associated with the hydraulic mechanism 33 and is specifically referred to since it is more fully illustrated in section in Fig. 1 and will at the same time describe the cylinder 41 associated with the mechanism 34. The cylinder 41 is provided with circular bosses 42 at each end which fit tightly into circular openings in

the arm 35 and are locked therein by circular fittings 43 abutting the right side of the arm and secured thereto by screws 44, the fittings being slightly larger in diameter than the bosses 42.

Formed in the fittings 43 and the cylinder bosses 42 are communicating passages 47 whereby motive fluid may be alternately entered into and exhausted from opposite ends of the cylinder in the operation of withdrawing the cores from the casting 19 and inserting them into or operationally associating them with the die parts 10 and 11. The fluid passages 47 are connected to a suitable motive fluid transmission (not shown) by ports 48 in the fittings 43. The motive fluid is directed to one end or the other of the cylinders 41 by control valves included in the system. Referring again to the mechanism 34 (Fig. 2), a piston 49 within the cylinder 41 carries a piston rod 50 which extends through the outer end of the cylinder, a packing gland 51 being interposed between the rod and the cylinder to provide a fluid tight fit. The outer end of the slide 38 is formed with a shouldered opening 54 within which is carried a shouldered circular collar 55 which is keyed as indicated at 56 to the outer end of the piston rod 50 to prevent relative rotation therebetween, the latter abutting the inner surface of the outer end of the slide. Formed axially in the piston rod 50 is a shouldered aperture 57 which is threaded at its outer end, the aperture in the collar 55 being correspondingly threaded. A screw 58 is threaded into the aperture 57 of the piston rod 50 and the aperture 35 of the collar 55, an enlarged outer end of the screw 58 cooperating with a stop surface 59 on an inner surface of an end member 60 of the arm 35 to limit the movement of the piston rod toward the right, as viewed in Fig. 2. The screw 40 58 is provided at its outer end with a depression for the reception of a tool which may be inserted through an aperture 62 in the member 60 of the arm 35 to adjust the screw. It will be apparent that the screw 58 and the key 56 serve 45 to rigidly connect the piston rod 50 to the slide 38 so that the latter will move at all times with the piston 49 and that by threading the screw inwardly or outwardly relative to the threaded apertures the distance the piston rod will travel 50 toward the right before the enlarged end of the screw 58 engages the stop surface 59 may be varied and thereby the movement imparted to the slide and the cores 28 carried thereby. The diameter of the aperture 54 of the slide 38 and 55 the collar 55 entered therein are such that the collar may freely move laterally to align itself with the screw 58, the thrust of the piston rod 50 upon the slide 38 during its movement in opposite directions being taken at the points 64 60 and 65. It will be noted that the hydraulic mechanism 33 is designed to provide for a greater movement for the slide 38 and the attached cores 27 to and from the die parts 10 and 11 than in the case of the mechanism 34. This permits a die casting machine equipped with the core actuating mechanism of this invention to be used to produce a greater variety of castings.

Removably secured to the left end of the slide 38 (Fig. 2) by upper and lower pairs of through bolts 66 is a core carrying adaptor plate 67, the bolts extending the full length of the slide. The plate 67 supports the cores 28 which may be variously arranged thereon to correspond with core apertures in the die parts 10 and 11 which are 75 shaped to form a particular casting and conse-

quently with different types of castings the plates may vary in length and width and within the capacity of the die casting machine being used. The cores 28, which are provided with heads at their inner ends, are inserted through shouldered apertures formed in the plate 67 and rigidly secured in position thereon by back-up screws 68. The movement of the cores 28 towards the left (Fig. 2) is limited by the engagement of the plate 67 with the die part 11. It will be understood 10 that the core supporting plate 67 may be provided with a plurality of variously arranged apertures of uniform size or varying in size so that different combinations of cores may be arranged thereon to correspond with the arrangement of 15 core apertures in different die parts 10 and 11. In some cases one core plate 67 may serve for several different die parts 10 and 11, the cores being inserted in particular apertures of the plate and omitted from the other apertures thereof. In the drawings only one set of apertures in the core plate is shown. Thus the plate 67 may be readily removed from the slide 38 to arrange for a different combination of cores there- 20 in or to change plates when setting up the machine for a different run of castings. 25

The stationary die supporting plate is provided with a plurality of predeterminedly spaced rows of threaded apertures 70, as clearly shown in Fig. 2, whereby die parts 11 of different dimensions for various castings within the capacity of the die casting machine may be fixed to the plate 13. The movable die part 10 and an ejecting mechanism for the castings, indicated at 69, are secured to the plate 12 in a suitable manner (not shown) which will permit different die parts 10 corresponding to different die parts 11 to be secured in position upon the plate 12. The die part 11 is secured to the plate 13 by screws 71 extending through apertures at each corner of the die part, the apertures in the latter being spaced for alignment with certain apertures 70 of the plate. It will be readily apparent that by suitably spacing the apertures 70 in the plate 13 a great number of different die parts 11 may be used on one machine. Thus it will be apparent different die parts 10 and 11 may be readily mounted upon the plates 12 and 13, respectively, which feature taken with the means for readily adapting the hydraulic core 45 actuating mechanisms to accommodate various arrangements of cores for corresponding dies provides a combination in a die casting machine which is very efficient, since it reduces the time required to set up the machine for a different 50 run of castings to a minimum, and provides a more universal die casting machine. 55

Referring particularly to Figs. 2 and 3 the molten metal enters the stationary die part 11 through a sprue 75 from a nozzle 76 and passes 60 through a gate 77 into the casting cavity 18 formed in the die parts 10 and 11. The molten metal is supplied to the nozzle 76 under pressure through the usual gooseneck employed in die casting machines of well known type, wherein the gooseneck may be either stationary or movable. The die part 11 is cooled by a suitable medium which traverses efficiently arranged circulating paths 80 and 81 (Fig. 2) formed in the body of the die part. Associated with inlet and outlet 70 ports of each of the paths 80 and 81 are yieldably self-adjusting joint connections 82 comprising a spring pressed shouldered pipe fitting 83 having a sliding fit in a shouldered aperture 84 in the plate 13, the inner end of the fitting having a 75

seat in the die part with a washer between the die part and the fitting. Between an enlargement on the fitting 83 and a shouldered surface of the aperture 84 is a compression spring 85, the spring 5 serving to firmly retain the fitting 83 against the washer in the seat in the die part 11 as to provide a fluid tight fit between the circulatory path and the fitting and to compensate for any wear between the parts. Furthermore, with this type of 10 connection for the cooling medium the changing of die parts is greatly facilitated since it is merely necessary to remove the die and position another die in its place, during which the disconnection and connection of the circulatory paths 15 80 and 81 from and to the fittings 83 are automatically made.

In the operation of the aforescribed mechanisms and as shown in the drawings, the die parts 10 and 11 have been closed by the movement 20 of the die part 10 into abutting relation with the stationary die part 11, the cores 26, 27, and 28 having been moved by their hydraulic actuating mechanisms into the casting cavity 18 of the die parts, and the molten metal injected through 25 the sprue 15 and the gate 17 from the nozzle 16 into the casting cavity around the cores inserted therein to form the casting 19. As the casting 19 starts to cool and shrink the cores 26, 27, and 28 are retracted from the casting by their respective 30 hydraulic actuating mechanisms, which as hereinbefore described, are connected to a motive fluid transmission system (not shown) through the ports 48, the motive fluid being directed to the inner end of the cylinders 41 by the control valves included in the system. The movement of the cores outwardly is determined by the adjustment of the screws 58 in the piston rods 50, the outer ends of the screws engaging 35 the stop surfaces 59. In timed relation with the retraction of the cores 26, 27, and 28 the die part 10 is moved away from the die part 11 and the casting ejected.

Although the invention has been described and 45 illustrated as to one specific embodiment, it will,

of course, be understood that the invention is not to be limited thereto, but is to be limited only by the scope of the appended claims.

What is claimed is:

1. In a die casting machine, a die supporting plate for interchangeably supporting a plurality of different dies having variously arranged cores for movement into and out of the corresponding die cavities, and core actuating means comprising a hollow slide mounted directly on said die 10 supporting plate for movement toward and away from the die, elongated slideways on the supporting plate extending substantially the full length of said slide for guiding the same in its movements, a motive fluid cylinder attached directly to the supporting plate within the hollow of said slide, a piston in said cylinder connected for actuating the slide, and a readily replaceable adaptor plate on the slide for connecting the slide interchangeably with variously arranged 15 cores of the different dies.

2. In a die casting machine, a die supporting plate for interchangeably supporting a plurality of different dies having paths formed therein for the passage of cooling medium therethrough and 20 variously arranged cores for movement into and out of the corresponding die cavities, and spring pressed cooling medium connections carried by said die supporting plate for automatically making 25 connections to the circulatory paths formed 30 in the plurality of different dies when interchangeably supported on the supporting plate, core actuating means comprising a slide mounted directly on said supporting plate for movement toward and away from the die, elongated slide- 35 ways on the supporting plate extending substantially the full length of said slide for guiding the same in its movements, a motive fluid cylinder attached directly to said supporting plate, a piston in said cylinder connected for actuating the 40 slide, and a readily replaceable adaptor plate on the slide for connecting the slide interchangeably with variously arranged cores of the different dies.

GEORGE L. CHERRY. 45
